(57) **CLAIM**

The ornamental design for an antenna array, as shown and described.

DESCRIPTION

FIG. 1 is a perspective view of a first embodiment of an antenna array according to my new design.

FIG. 2 is a top view thereof.

FIG. 3 is a front side view thereof.

FIG. 4 is a rear side view thereof.

FIG. 5 is a left side view thereof; the right side view being a mirror image thereof.

FIG. 6 is a perspective view of a second embodiment of an antenna array according to my new design.

FIG. 7 is a top view thereof.

FIG. 8 is a front side view thereof; the rear side view being a mirror image thereof.

FIG. 9 is a left side view thereof; the right side view being a mirror image thereof.

FIG. 10 is a perspective view of a third embodiment of an antenna array according to my new design.

FIG. 11 is a top view thereof.

FIG. 12 is a front side view thereof.

FIG. 13 is a rear side view thereof; and,

FIG. 14 is a left side view thereof the right side view being a mirror image thereof.

The dash-dash-dash broken lines in the drawings depict environmental subject matter only and form no part of the claimed design. The dash-dot-dash lines in FIGS. 1, 2, 6 and 7 represent a boundary line and form no part of the claimed design. In FIGS. 10-14, the blank surface representing the substrate supporting the antenna array forms no part of the claimed design.
